UNITED STATES PATENT OFFICE.

WESTON GREEN, OF CHICAGO, ILLINOIS.

DESIGN FOR A DIAPER.

SPECIFICATION forming part of Design No. 25,343, dated March 31, 1896.

Application filed February 24, 1896. Serial No. 580,522. Term of patent 14 years.

To all whom it may concern:

Be it known that I, WESTON GREEN, a citizen of the United States, residing at Chicago, in the county of Cook and State of Illinois, 5 have invented and produced a new and original Design for Diapers, reference being had to the accompanying drawing, forming a part hereof.

In the accompanying drawing, the figure 10 represents a plan view of my design laid out in a flat plane.

The leading feature of my design consists in a substantially triangular main portion and projecting lap portion.

A is the triangular main portion, having 15 the portions a , a' , and a'' and the projecting lap portion B, the whole presenting to the eye a harmonious and ornate figure, as illustrated in the drawing.

I claim—

20 The design for a diaper herein shown and described.

WESTON GREEN.
